UNITED STATES PATENT OFFICE.

PLEASANT B. HUFFMAN, OF CHANDLERVILLE, ILLINOIS, ASSIGNOR OF ONE-HALF TO GEORGE W. LEEPER AND HENRY S. LEEPER, OF SAME PLACE.

CURTAIN-FIXTURE.

SPECIFICATION forming part of Letters Patent No. 402,598, dated May 7, 1889.

Application filed January 18, 1889. Serial No. 296,701. (No model.)

To all whom it may concern:

Be it known that I, PLEASANT B. HUFFMAN, a citizen of the United States, residing at Chandlerville, in the county of Cass and State 5 of Illinois, have invented a new and useful Improvement in Curtain-Fixtures, of which the following is a specification.

The invention relates to curtain-fixtures of that class in which a roller shade or curtain 10 is adjustable vertically with relation to the window-frame, so that any desired portion of the window may be darkened by unrolling a part of the shade and adjusting it in the desired position; and the invention consists in 15 the improved construction and combination of parts which will be hereinafter fully described, and particularly pointed out in the claims.

In the drawings, Figure 1 is a front view of 20 a window equipped with my improved adjustable roller-shade, showing the latter partly unrolled and lowered, so as to shade the middle part of the window. Fig. 2 is a front view showing the shade raised to the top of the 25 window-frame and wound upon the roller. Fig. 3 is a perspective detail view of one end of the curtain-roller, showing how it is connected with the operating-cord. Fig. 4 is a detail view of one of the links connecting the 30 ends of the curtain-roller with the operating-cord.

The same letters refer to the same parts in all the figures.

In the drawings, A designates a window-frame of ordinary construction, at the top and bottom of which are centrally located screw-eyes B' B², while at the four corners are additional screw-eyes B³, B⁴, B⁵, and B⁶.

C is a light but strong operating-cord, which 40 passes upward through the upper central screw-eye, B', thence laterally to one of the upper corners, through the screw-eye B³ at said corner, downward and through screw-eye B⁴ at the corresponding lower corner, thence 45 to the lower central screw-eye, B², up through the latter and through the upper central screw-eye, B', thence to the upper corner screw-eye, B⁵, down through the latter and through the lower corner screw-eye, B⁶, thence 50 again to the lower central screw-eye, B², and up through the latter. The ends of the cord

are then tied together or otherwise suitably connected, thus making an endless cord, by pulling upon which at any point the sides or parts between the screw-eyes B³ B⁴ and B⁵ B⁶ 55 will move simultaneously in the same direction.

In lieu of the screw-eyes, pulleys of any suitable construction may be used, double pulleys being of course necessarily put in the 60 places of the upper and lower central screw-eyes, B' and B².

D is the roller, to which is attached a curtain or shade, E. The ends of the roller are provided with annular grooves F, and it is attached to the endless cord C or the parts thereof between the corner screw-eyes, B³ B⁴ and B⁵ B⁶, by making a turn of the cord or winding it once around each end of the roller in the grooves F, which prevent the cord from 70 slipping off.

To retain the shade-roller in the proper position upon the cord and prevent it from slipping or dropping at either or both ends, I employ the links G, (shown in Fig. 4 of the drawings,) which links may be constructed of wire, and consist of a central bent or curved portion, a, at the ends of which are formed eyes b b. The bent middle portion of said links will fit over the front side of the roller, above 75 and below which the eyes b b are hooked or adjusted upon the endless cord C, thus creating sufficient friction to prevent the accidental displacement of the roller.

The shade E is provided at its lower end 85 with the usual stiffening-slat, H, to the ends of which are attached a pair of loops, I I, through which the endless cord passes at the sides of the window-frame. This is for the purpose of preventing the shade, when partly 90 or entirely unrolled, from fluttering or being blown into the room when the window is open.

The ends of the roller are provided with laterally-extending pins J J, located axially with relation thereto. Near the upper end of 95 the window-frame at the sides thereof are secured a pair of arms or brackets, K K, registering with said pins, which bear against the under sides of the said arms or brackets when the roller is drawn up to the top of the window-frame.

To the slat H, at the lower end of the shade,

may be attached a ring or tassel, L, for unrolling the shade.

The operation of my invention will be readily understood from the foregoing description, taken in connection with the drawings hereto annexed. The shade may be unrolled to any desired extent by simply pulling the ring or tassel at its lower end. It may then be adjusted to any desired position by pulling upon the cord C, preferably by grasping the parts of said cord between the central screw-eyes, B' B². When said parts of the endless cord are grasped and pulled upwardly, the sides of the cord between the corner screw-eyes, B³ B⁴ and B⁵ B⁶, will travel downwardly, carrying the shade-roller, which is meanwhile retained securely upon the cord by the friction-links G G. In order to wind the shade upon the roller, the latter is first raised to the top of the window-frame by pulling the cord C in the proper direction until the pins J J bear against the under sides of the brackets K K. By continuing to pull in the same direction the roller will be revolved by the cord C being wound once around each end thereof, as desired. It will be seen that when this is done the position of the cord is shifted with relation to the roller and the screw-eyes, the result of which is that the cord will not be worn excessively at any particular place, but gradually and evenly throughout its entire length, thus rendering it more durable and less liable to breakage. The general construction of the device is simple and inexpensive and it may easily be put up and manipulated.

I would state that it is not deemed necessary that the screw-eyes B' B² should be located centrally at the top and bottom of the window-frame, as they may be located near either side with the same results.

Having thus described my invention, I claim—

1. The combination, with a window-frame, of screw-eyes located at the middle of the top and bottom of said frame and at its four corners, an endless cord threaded through the said screw-eyes, as described, crossing itself between the middle screw-eyes, and a shade-roller attached to the parts of the said cord between the upper and lower corner screw-eyes, substantially as described.

2. The combination, with a window-frame, of screw-eyes located at the middle of the top and bottom of said frame and at its four corners, an endless cord threaded through the said screw-eyes, as described, crossing itself between the middle screw-eyes, and a shade-roller having annular grooves near its ends, attached to the parts of said cord between the upper and lower screw-eyes by winding

said cord once around each end of the roller in the grooves in the latter, substantially as set forth.

3. The combination, with a window-frame, of screw-eyes at the middle of the top and bottom and at the four corners thereof, an endless cord threaded through said screw-eyes, as described, a shade-roller attached to said cord by winding the parts of the latter between the corner screw-eyes once around each end of the roller, and friction-links having eyes, whereby they are adjusted upon the endless cord at each end of the roller, so as to bear against the latter, substantially as set forth.

4. The combination, with a window-frame, of screw-eyes at the middle of the top and bottom and at the four corners thereof, an endless cord threaded through the said screw-eyes, as described, a shade-roller attached to said cord by winding the latter once around each end of the roller, a stiffening-slat at the lower end of the shade, and loops attached to the ends of said slat and encircling the endless cord, substantially as set forth.

5. The combination, with a window-frame, of screw-eyes at the middle of the top and bottom and at the four corners thereof, an endless cord threaded through said screw-eyes, as described, a shade-roller attached to said cord by winding the latter once around each end of the roller, axial pins extending from the ends of the roller, and brackets secured near the upper corners of the window-frame to form bearings for the said pins, substantially as set forth.

6. As an improvement in curtain-fixtures, the combination, with a window-frame, of screw-eyes at the middle of the top and bottom and at the four corners thereof, an endless cord threaded through said screw-eyes, as described, a shade-roller attached to said cord by winding the latter once around each end of the roller, friction-links adjusted upon the endless cord over and bearing against each end of the roller, axial pins extending from the ends of the latter, brackets secured near the upper corners of the window-frame to form bearings for the said pins, and loops at the lower corners of the shade encircling the endless cord, all arranged and operating substantially as set forth.

In testimony that I claim the foregoing as my own I have hereto affixed my signature in presence of two witnesses.

PLEASANT B. HUFFMAN.
